UNITED STATES PATENT OFFICE.

JOSEPH HUTCHINSON, OF MONTREAL, QUEBEC, CANADA.

RESTAURANT SERVICE DEVICE.

1,397,809.

Specification of Letters Patent. Patented Nov. 22, 1921.

Application filed February 12, 1920, Serial No. 358,048. Renewed October 4, 1921. Serial No. 506,031.

To all whom it may concern:

Be it known that I, JOSEPH HUTCHINSON, a citizen of the United States of America, residing at Montreal, Province of Quebec, 5 Canada, have invented certain new and useful Improvements in Restaurant Service Devices; and I do hereby declare that the following is a full, clear, and exact description of the invention, such as will enable 10 others skilled in the art to which it appertains to make and use the same.

The present invention has reference to a mechanical service adapted for use more particularly in connection with restaurants, 15 which will perform the function of human attendants at the table of the restaurant, as set forth in my former Patent No. 1,215,536, dated February 13th, 1917. Herebefore, there have been many ways of utilizing conveyors for bringing dish trays from and to the kitchen and the trays when carried from the kitchen being automatically deposited at predetermined tables in the dining room, but such mechanical devices have met with great 25 disfavor, due to the fact that the trays are deposited upon the tables or are only left upon the tables for a limited time, which requires that the customer remove the dishes from the trays. The principal object of the 30 present invention is to provide a mechanical restaurant service which will carry the dishes upon a tray from a kitchen, pantry or the like, deposit the dishes upon the table, and return the trays to the kitchen.

35 A further object of the present invention is to provide a device of this character which will carry the trays from the kitchen, automatically depositing the dishes upon the dining room tables, and the depositing of the 40 dishes upon the dining room tables may be predetermined, so that the dishes called for may be deposited upon the respective tables within the dining room.

45 With the above and other objects in view which will hereinafter appear as the description continues, the invention consists of the novel features of construction, combination and formation of parts as will be hereinafter more fully described and particularly pointed out in the appended claims.

50 In the accompanying drawings has been shown a simple and preferred form of the invention, it being, however, understood that no limitation is necessarily made to the precise structural details herein exhibited, but the right is hereby reserved to any

changes, alterations or modifications to which recourse may be had that come within the scope of the claims without departing from the spirit of the invention or sacrificing 60 the efficiency of the same.

In the accompanying drawings:

Figure 1 is a plan view of a portion of the mechanism embodying the present invention having the housing therefor broken away; 65

Fig. 2 is a detail side elevation showing the door closing the opening leading to one of the tables;

Fig. 3 is a similar view showing the door in open position; 70

Fig. 4 is a fragmental transverse section looking toward the front of one of the conveying trays;

Fig. 5 is a similar view looking at the rear of one of the conveying trays and illustrating 75 a portion of the table within the dining room;

Fig. 6 is an enlarged sectional view through a cam supporting member;

Fig. 7 is a detail perspective view of the 80 tray when in its normal position;

Fig. 8 is a detail elevation of the same when the tray is about to return to its normal position;

Fig. 9 is a detail plan view of one of the 85 dish trays showing its position when traveling from the kitchen to the dining room;

Fig. 10 is a similar view showing the first movement of the tray when about to deliver the dishes to the table within the dining 90 room.

Fig. 11 is a similar view showing the position of the tray when it has deposited the dishes upon the table within the dining room; and, 95

Fig. 12 is a similar view showing the tray when returning to its normal position.

Referring now more particularly to the accompanying drawings wherein like and corresponding parts are designated by similar reference characters throughout the 100 several views.

In the accompanying drawings, I have illustrated a portion of a suitable housing for inclosing a mechanical restaurant service which consists of the side walls 1 and 2 respectively and a bottom 3. This casing may represent a dividing wall within a room, or it may be portable as desired, but extends from the kitchen in a restaurant 105 to the dining tables. In Fig. 1, I have illustrated the walls 1 and 2 each having the 110

alining openings 4 therein, which openings are adapted to be normally closed by means of the vertical slidable doors 5. Ranged adjacent each of these openings 4 and exteriorly of this casing are the tables 6, and these tables are positioned within the dining room so that the customer may receive the ordered dishes containing food thereupon. These tables may be ordinary dining room 10 tables fully set for a customer, and after the customer has given his order for the desired dishes, the latter will be automatically conveyed to him and deposited upon the table, thereby eliminating human attendants at 15 the tables within a restaurant. In this Fig. 1, I have illustrated the tables as being positioned at both sides of the casing, so that the trays may be alternately swung to deposit the dishes upon the table, but, of course, it will be understood that this mechanism may be effectively used in depositing the dishes at only one side of the casing, or the casing may be eliminated entirely and the conveyer extended to each side of the 25 tables.

Arranged within this housing or casing is a plurality of supports 7 carrying the tracks 8 and disposed to ride upon these tracks 8 are the carriages 9. These carriages 9 are suitably connected to the links of an endless conveying chain or belt which extends from the kitchen of the restaurant throughout the entire length of the housing. This conveyer chain or belt moves continuously in one direction, so that the carriages connected to the upper portion 10 of the belt will deliver the trays, and the dishes carried thereby may be deposited within the lunch room; then the lowest section 11 of 40 the conveyer returns the trays to the kitchen.

Secured to each carriage 9 is a platform 12 and mounted upon this platform 12 is a vertical shaft 13 having suitably connected to its upper end a segment 14. Rotatably 45 and slidably mounted upon this shaft 13 is a bar 15 which carries one of the trays, and each tray consists of a plurality of horizontally extending bars or fingers 16 which are equally spaced apart, and upon these bars 50 or rods 16 are deposited the dishes which are conveyed from the kitchen and finally deposited upon the tables 6. This bar 15 has an oppositely projecting arm 17 and connecting this arm 17 with the platform 12 55 is a coil spring 18 which has a tendency to exert a pull upon this bar 15 in two directions, that is, it normally tends to hold the bar 15 and the tray carried thereby in the position as better shown in Figs. 1, 7 and 9, 60 but at the same time permits the bar 15 to oscillate about the shaft 13 for a purpose which will be later described. This coil spring 18 being connected to the platform 12 has also a downward pull upon the bar 15, 65 the purpose of which will also be later set

forth. Carried by this bar 15 is an L-shaped bracket 19 which is adapted to ride upon the segment 14 for holding the tray and bar 15 in an elevated position, but when the bar 15 has been moved so that the bracket 70 19 will pass over the free end 20 of the segment 14, the tray and bar will be pulled downwardly and return to its normal position, but this L-shaped bracket 19 will pass beneath the segment 14 to a position where 75 it may again be placed upon the segment.

When a tray leaves the kitchen, it is elevated and retained in this elevated position by permitting the bracket 19 to rest upon the segment 14, and as the conveyer 80 is continuously in motion, it will, of course carry the tray through the housing or casing. This tray 16 is adapted to swing in a horizontal plane, so that it may enter one of the openings 4, and after it has entered 85 one of these openings, the prongs or rods of the tray will pass through a similar set of rods or prongs 21 which are provided at proximity of the tables 6, and as the tray passes through the bars 21, the dishes carried by the tray will, of course, press upon the bars 21 forming a receiving platform 90 at proximity of the table.

For effecting the movement of the trays, I provide the plates 22 each of which being provided with a cam face 23 upon which is adapted to ride the arm 17 of the bar 15. The conveyer moves in the direction of the arrow, as shown in Fig. 9, and as the arm 17 comes in contact with the 95 cam 23, it will ride thereupon, causing the tray to first swing to the position as illustrated in Fig. 10 and finally to the position as shown in Fig. 11, where the rods of the tray will extend above the rods 21 100 of the table. When the bar 15 is in the position as shown in Fig. 11, the bracket 19 will ride over the end 20 of the segment 14, and the spring 18, assisted by the weight 105 of the tray and the dishes thereupon, will drop so that the bars of the tray 16 will immediately pass through the bars 21 of the receiving platform leaving the dish A upon the bars 21, and the spring 18 will immediately cause the bar 15 to return to its normal position which is transversely of the platform 12 and substantially positioned as 110 shown in Fig. 9. The return movement of the tray is better illustrated in Fig. 12, and the bracket 19 will, of course, swing below the segment 14 on its return movement, but as the tray approaches the kitchen, suitable means, (not shown) which may be either mechanical or manual, may be used for again raising the bar 15 and placing the 115 bracket 19 upon the segment so that it will assume the position as better illustrated in Fig. 7. The slidable doors 5 normally close the openings 4 and are retained in this closed position by means of the pivotally 120 125 130

mounted latch member 24. When this latch member 24 is in the position as shown in Fig. 2, it will hold the door in its uppermost or closed position, but when this 5 latch 24 has been released or operated, as shown in Fig. 3, the door 5 will be released and permitted to fall by gravity. As this door 5 normally closes the opening 4, the tray, of course, cannot enter this opening 10 until the door has been released, and therefore I provide means automatically for releasing this latch member 24, so that the door may be opened when it is desired to pass a tray through the opening. Connected 15 to this door 5 is a cable 26 which extends over suitable pulleys as shown, and connected to this cable 26 is a block 27 which is mounted upon a suitable track 28. When this block 27 is moved to the 20 position as better shown in Fig. 2, the door 5 will be closed, but when the door is opened, this block 27 assumes a position upon the track 28 as better illustrated in Fig. 3.

25 The trays 16 may be automatically controlled so that they will move at the desired time they deposit the dishes carried thereby upon a predetermined receiving platform, and the door closing the opening will be automatically released so that the tray at the desired time may enter the opening leading to this predetermined receiving platform. Also, after the tray has delivered the dishes, it will not only return 30 to its normal position and be carried back to the kitchen, but the door way through which it has passed will again be closed by elevating the door therefor. The automatic control of the trays may be operated from 35 the kitchen.

Slidably mounted upon the platforms 12 are a plurality of bars 29, each carrying a 40 knob 30, and the knobs having alphabetical indications thereupon or any other suitable 45 designating marks. Pivotally connected as at 31 to the forward ends of the platforms 12 are the bars 32, and these bars 32 are connected by means of the links 33 to the bars 29. When one of the knobs 30 has been 50 pushed inwardly as better shown in Fig. 9, the bars 32 connected thereto will be depressed so as to assume a vertical position as better shown in dotted lines in Fig. 8. There, of course, will be as many knobs 30 55 as there are tables adjacent to the main housing, and the platforms 12 may be so arranged that the trays will be alternately caused to swing through the openings 4 at both sides of the housing. When it is de- 60 sired to cause the tray 34 to swing and deposit the dish carried thereby upon the receiving platform 35, as illustrated in Fig. 1, the knob 30 designated by the letter A is pushed forward, but if the attendant within 65 the kitchen desires this tray 34 to deposit its

dishes upon the table 36, the knob 30 designated by the letter B will be pushed forward likewise. From this it is obvious that there may be as many knobs 30 as there are tables along one side of the housing, and each 70 table will be designated upon one of the knobs 30. When operating the knob 30 designated by the letter A, the tray must be actuated so that it will deposit the dishes carried thereby upon a receiving platform 75 35. As the bar 32 connected to this knob is in a vertical position, it will, during its course of travel through the housing, strike the upper face of the shoe 37 which is arranged within the path of travel of this 80 bar 32 and is adapted to actuate other mechanism which will release the bar 15 and cause the tray to swing upon its pivoted support. This shoe 37 is connected by means of the links 38 to a suitable support 39, and a leaf 85 spring 40 normally holds this shoe 37 in an elevated position as better illustrated in Fig. 2, but when the bar 32 rides upon this shoe 37 in the manner as illustrated in Fig. 3, the shoe, of course will be forced downwardly 90 and forwardly. The cam plate 22 is supported by means of a vertical bar 41 and this bar 41 is slidably mounted within a support 42. A coil spring 43 normally holds the bar 41 and the plate 22 in an elevated position as better shown in Fig. 6. The support 42 has a vertical slot 43' formed therein through which extends a rod 44 carried by the support 41 and this rod 44 extends beneath the shoe 37. When this shoe 37 has 100 been depressed, the support 41 and plate 22 will be forced to move downwardly, whereby the cam plate 22 will be brought within the path of travel of the arm 17, and as the conveyer continues its travel, the tray will 105 be caused to swing upon its support as has been previously described. The latch member 24 is connected through a suitable rod and link connection 45, as shown, to a pawl 46, and the latter is pivotally supported upon 110 the supporting block 39. This pawl 46 is arranged at the forward end of the shoe 37, and when the shoe 37 is actuated by the bar 32, it will move forward, thereby actuating the pawl 46 as illustrated in Fig. 3, so that 115 the latch member 24 will be released and the door 5 permitted to drop, thereby opening the doorway and permitting the tray to pass therethrough. After the tray has delivered its dishes upon the receiving table, 120 it is desirable to close this door way and therefore the door 5 has to be elevated. The conveyer which is in continual motion will carry the bar 32 along until it strikes the block 27 which is within the path of travel 125 of the bar 32, and this block 27 will, of course, be carried with the conveyer until it is permitted to drop within the inclined portion 47 of the track 28, where it will be beneath the lower end of the bar 32, so that 130

the block 27 will be released. When this block 27 has been moved to this position, the latch 24 has also been released and will retain the door 5 in its elevated position, and 5 the block 27 will be free to return to the position as shown in Fig. 3 when the door is again opened. It is, of course, to be understood that the shoes 37 and the blocks 27 arranged adjacent each doorway are in the 10 path of travel of the respective bars 32, and unless one of these knobs 30 has been moved, that the tray may travel with the conveyer through the housing in an undisturbed manner, and that by having a knob 30 for each 15 door way, the tray will be caused to move at the predetermined time and deposit the dishes upon the predetermined table.

From the foregoing, it is apparent that a customer seated at one of the tables 6 may 20 give an order in any suitable manner to the attendant within the kitchen of the restaurant. After the attendant has this order given and the dishes prepared, they are placed upon one of the trays 16. The knob 25 30 representing the table at which the customer is seated will then be moved forward and the dishes carried on their way by the conveyer. As the tray containing the dishes approaches the platform to receive the same, 35 the door 5 adjacent that platform will be opened and the tray swung within the door way, whereby the dishes will be deposited upon the bars 21. The tray is again returned to its normal position and travels 40 back to the kitchen. Likewise the door 5 closes the opening leading to the occupied table. The customer may then take the dishes from the bars 5 and properly place them in front of himself upon the table, 45 thereby having efficient and mechanical restaurant service which will eliminate human attendants for the customer.

Having thus fully described my invention, what I claim as new and desire to secure by Letters Patent is:

1. In a restaurant service device the combination with a tray carrier and receiving platforms arranged adjacent thereto, means for automatically moving said trays where 50 by they will be caused to travel through the receiving platforms and the dishes carried thereby caused to remain upon the receiving platforms.

2. In a device of the character described 55 the combination with a dish tray carrier and a plurality of receiving platforms for receiving the dishes carried by said trays, means for automatically moving said trays whereby they will be caused to be positioned 60 upon said receiving platforms, and means for releasing said trays whereby the dishes will be deposited upon said tables.

3. In a device of the character described 65 the combination with a dish tray carrier and a plurality of receiving tables, means ar-

ranged adjacent each table for causing the dishes carried by the trays to be deposited upon the receiving tables, and means carried by the carrier whereby a predetermined dish removing means may be brought in operation.

4. In a device of the character described the combination with a housing having a dish tray carrier arranged therein, of a plurality of receiving platforms arranged adjacent said housing, door controlled openings arranged within said housing and adjacent said platforms, means for automatically actuating said trays whereby they will deposit the dishes upon said receiving platforms, and means for automatically opening said doors, when said trays have been actuated.

5. In a restaurant service device, the combination with a kitchen, a plurality of trays 85 for carrying dishes, and a dining room having tables therein, of means for mechanically conveying the trays and dishes carried thereby from the kitchen to the dining room, automatically removing the dishes from the trays and depositing the same upon the tables, and means for mechanically returning the trays to the kitchen.

6. In a restaurant service device comprising a continuously traveling conveyer, dish-carrying trays supported thereby, and means for actuating said trays whereby the dishes will be removed therefrom.

7. In a restaurant service device, the combination with a kitchen, trays for carrying dishes, and a dining room having tables therein, of means for carrying said trays from the kitchen to said dining room, means for moving said trays toward the tables within the dining room, and means for causing the dishes carried by the trays to be deposited upon the tables.

8. The combination with a continuously traveling carrier, article-carrying trays secured thereto, means for laterally swinging said trays with respect to said carrier, and means for removing the articles carried by the trays when they have been swung in their lateral positions.

9. In a restaurant service device, the combination with a tray carrier and receiving tables for the reception of the articles carried by the trays of said carrier, of means for automatically moving the trays from the carriers toward the tables whereby the articles carried by the trays will be deposited upon the tables.

10. In a restaurant service device, the combination with dish trays and dining room tables having receiving platforms arranged adjacent thereto, of means for conveying said trays toward said tables, and means for moving said trays whereby the dishes carried thereby will be deposited upon the receiving platforms.

11. In a restaurant service device, the combination with dish trays and dining room tables, of means for conveying said trays, and means whereby each tray may be moved adjacent any predetermined table for depositing the dishes carried by the tray upon the table substantially as and in the manner specified. 5
12. In a restaurant service device, the combination with a dish tray carrier and tables, of means for actuating said trays whereby the articles carried thereby may be deposited upon receiving platforms near the tables, and means carried by said trays for causing the actuating means to be brought into operation at a predetermined table, substantially as and for the purpose specified. 10
13. In a restaurant service device, the combination with a carrier and tables for receiving the dishes, of dish trays secured to said carrier, means for causing the trays to move toward either side of the carrier for depositing the dishes upon receiving platforms near the tables, and means for returning the trays after the dishes have been removed. 15
14. In a restaurant service device, the combination with a conveyer and a plurality of receiving tables, of a plurality of article-carrying trays secured to said conveyer, means for automatically operating said trays whereby they will be caused to move toward said tables and deposit the articles thereupon, and automatic means for causing the trays to be returned from the tables. 20
15. In a device of the character described, the combination with a plurality of dish-carrying trays, a conveyer having the trays permanently fixed thereto and adapted to move in one direction to deliver the trays, means for moving the trays in another direction, and means for removing the dishes from the trays after they have been moved in the last mentioned direction. 25
16. The combination with a dish tray carrier and a plurality of dish-receiving platforms, of means for causing said trays to travel adjacent to said platforms, and means for automatically controlling the trays whereby each tray may be caused to deposit the dishes carried thereby upon a predetermined platform. 30
17. In a device of the character described, the combination with a dish tray carrier and a receiving platform, a partition arranged between the said platform and carrier, a door-controlled opening arranged within said partition, means for automatically moving said tray through said opening adjacent said platform, after the door for said opening has been completely opened, and means for automatically closing said door after said tray has been completely removed from said opening. 35
18. The combination with a dish tray and a platform for receiving the dishes carried by said tray, a partition arranged between said tray and said platform, a door-controlled opening arranged within said partition, means for automatically moving said tray through said opening whereby the dishes may be deposited upon the platform, means for opening said door when the tray has been operated, means for withdrawing the tray through said opening, and means for automatically closing said door after said tray has been removed from said opening. 40
19. The combination with a carrier and a plurality of dish-receiving platforms, of a plurality of dish trays secured to said carrier, means arranged adjacent each platform whereby the trays will be caused to deposit dishes carried thereby upon the platforms, and means carried by said carrier for controlling each tray-actuating means at a predetermined time. 45
20. In a device of the character described, the combination with a conveyer and a plurality of dish-receiving platforms, dish-carrying trays secured to said conveyer, said conveyer adapted to move in one direction to deliver the trays, means for causing the trays to be swung to the opposite sides of the conveyer, means for causing the trays to pass through said receiving platforms whereby the dishes carried thereby may be deposited thereupon, and said conveyer being adapted to move in another direction to return said trays. 50
21. In a restaurant service device, the combination with a conveyer and a plurality of receiving tables, of a platform secured to said conveyer, a tray pivotally mounted upon said platform, and means arranged adjacent each table whereby said tray may be caused to move toward the tables substantially as and for the purpose specified. 55
22. In a restaurant service device, the combination with a conveyer and a plurality of receiving tables, of a plurality of trays mounted upon said conveyer, said trays consisting of a plurality of rods having their outer ends open, and means arranged adjacent each table whereby said trays will be caused to move toward the table and pass therethrough substantially as and for the purpose specified. 60
23. In a restaurant service device, the combination with a conveyer, a plurality of dish-carrying trays permanently fixed to said conveyer, a plurality of receiving tables spaced from said conveyer, and means for causing said trays to move toward said tables whereby the dishes may be deposited thereupon. 65
24. In a restaurant service device, the combination with a conveyer, a plurality of dish-carrying trays permanently fixed to said 70

- conveyer and normally retained in one position, receiving tables spaced from said conveyer, means for causing said trays to move toward said tables whereby the dishes may be deposited thereupon, and means for returning the trays to their normal positions substantially as and in the manner specified. 5
25. In a restaurant service device, the combination with a carrier, platforms permanently fixed to said carrier, dish-carrying trays movably supported upon said platforms, a plurality of receiving tables, means for causing said trays to move toward said tables whereby the dishes carried by the trays will be deposited upon said tables, and means for returning said trays to their normal positions upon said platforms. 10
26. In a restaurant service device, the combination with a conveyer, platforms mounted upon said conveyer, trays movably mounted upon said platforms, a plurality of receiving tables, and means carried by said platforms whereby said trays may be caused to move at a predetermined point and the dishes carried by the trays deposited upon said receiving tables. 15
27. In a device of the character described comprising in combination an article-supporting tray, a receiving platform, means for movably supporting said tray, and means for automatically moving said tray whereby it will be caused to pass through said platform and deposit the articles carried thereby upon said platform. 20
30. 28. In a restaurant service device, the combination with a conveyer, platforms mounted thereupon, trays movably supported upon said platforms, a plurality of receiving ta- 35
- bles, a partition arranged between said receiving tables and conveyer, door-controlled openings arranged within said partition, controlling means arranged adjacent said openings for opening and closing said doors, and means carried by each platform whereby said controlling means may be operated and the trays caused to pass through said openings whereby the dishes carried by said trays may be deposited upon said tables substantially as and for the purpose specified. 40
29. In a restaurant service device, the combination with a traveling conveyer, a plurality of platforms permanently fixed upon said conveyer, dish-carrying trays arranged upon said platforms, a plurality of receiving tables, controlling means arranged adjacent each table, actuating means carried by said platforms and adapted to coöperate with said controlling means whereby said trays will be caused to deposit the dishes carried thereby upon said tables substantially as and in the manner specified. 45
30. In a restaurant service device, the combination with an endless conveyer, receiving tables arranged adjacent said conveyer, platforms permanently fixed to said conveyer, an arm pivotally mounted upon each platform, a tray carried by each arm, means for retaining said arm in one position, and means for swinging said arm whereby said tray will be caused to deposit the articles carried thereby upon said receiving tables substantially as and for the purpose specified. 50

In witness whereof I have hereunto set my hand.

JOSEPH HUTCHINSON.
